UNITED STATES PATENT OFFICE.

JOHN W. PITT, OF BATH, NEW YORK.

BASE FOR PRINTING PLATES.

Application filed March 15, 1923. Serial No. 625,277.

To all whom it may concern:

Be it known that I, JOHN W. PITT, a citizen of the United States, residing in the city of Bath, county of Steuben, State of New York, have invented certain new and useful Improvements in Bases for Printing Plates, of which the following is a specification, reference being had to the accompanying drawings, forming a part 10 thereof.

The purpose of this invention is to provide an improved construction of a base for printing plate of the general class and character of those shown in patents of Hoge 15 and Ribe, Nos. 1,028,821 and 1,031,267. It consists in the elements and features of construction shown and described as indicated in the claims.

In the drawings:

20 Figure 1 is a plan view of a base embodying this invention.

Figure 2 is a section of the encompassing frame at the line 2—2 on Figure 1 with the partition plates and blocks removed.

25 Figure 3 is a section of the entire encompassing frame at the plane indicated at the line 3—3 on Figure 2.

Figure 4 is a plan view of a portion of the device at a certain stage in the process 30 of assembling the elements.

Figures 5 and 5^a are detail sections at the lines 5—5 and 5^a—5^a on Figure 4.

Figure 6 is a plan view of the device at a later stage in the assembling and with 35 all the blocks placed in their respective cells but without certain of the intersecting positions of one set, the other side and the other end constituting a diagonally opposite rigid angle of the frame being shown in position ready to be moved into engagement with the parts of the other rigid angle and with the partitions of the set which is complete in the assemblage.

Figure 7 is a perspective view of the 40 partitions which are lacking in Figure 6 showing them from the outer side.

Figure 8 is a similar view of the same partitions seen from the opposite side.

Figure 9 is a detail section at the line 45 9—9 on Figure 1.

Figure 10 comprises a perspective view of each of the three forms of blocks employed.

The construction shown in the drawings 50 comprises when completed a rigid rectangular encompassing frame consisting of side

bars, 1, 1, and end bars, 2, 2, which are distinguished as sides and ends merely for convenience of description and not because of any difference between the two dimensions of the parts. When completed the four 55 frame bars are rigidly secured at their corners forming four rigid angles and the space which they encompass is subdivided into cells by two sets of intersecting partitions, 3^a, 3^b, 3^c, 3^d, 3^e, and 4^a, 4^b, 4^c, 4^d, 4^e, 60 said sets being hereinafter distinguished as the first and second sets respectively. As shown these partitions are all oblique to the frame bars forming therefore in addition to rectangular cells certain right angular marginal cells each half the area of the rectangular cells and forming at each of the four corners a right angular cell one-fourth the area of the rectangular cells.

The cells are occupied by corresponding 75 ly shaped and dimensioned blocks all indicated by the reference character, N, and distinguished by individual exponential characters. The partitions of the two sets intersect each other at the planes of the inner faces of the frame bars; and the latter therefore have vertical or transverse slots, 6 and 7, for engaging the partition ends which meet and intersect at said inner faces of the frame bars as seen in Figure 2. The partitions of the first set have notches, 9, through half their width from the upper edge for interlocking with the partitions of the second set which have reciprocal notches, 10, from their lower edges 80 for such interlocking. The partitions of the first set are entered longitudinally into the slots, 6, of the frame bars, and are prevented from being entered or withdrawn vertically or transversely of the frame bars 85 by having horizontal longitudinal ribs, m, at their end portions which engage horizontal slots, 8, which are cut in the frame bars midway in their height across the intersecting slots, 6 and 7.

The partitions of the second set are entered into the slots, 7, of the frame bars vertically, or transversely of said bars and partitions, and are prevented from entering or withdrawing longitudinally or horizontally by their intersecting engagements with previously entered partitions of the first set, viz, at the notches, 9 and 10, of said partitions respectively.

The inner faces of the frame bars and 110

the faces of the partitions have horizontal ribs all designated, m , certain of them being hereinafter distinguished individually by exponential numerals; and the 5 blocks, N , have horizontal grooves, n , distinguished by different numeral exponents for engaging said ribs to prevent withdrawal of either partitions or blocks transversely from the frame; and the partitions 10 and blocks thus mutually lock each other against such withdrawal from the frame after the frame is completely closed up by and securement at diagonally opposite corners, as hereinafter described, of the two 15 rigid angles each comprising a side bar, 1, and an end bar, 2, forming the other two diagonally opposite corners of the frame, and by the insertion and securing of the final partition, 4^e , of the second set as hereinafter particularly described.

The detail construction as to presence and omission of the horizontal ribs on the walls of selected cells is designed with a view to facilitating assembling of the elements; and 25 these details will now be described.

One rigid angle of the encompassing frame being formed by securing rigidly together an end bar, 1, and a side bar, 2, the 30 first set of partitions, 3^a , 3^b , 3^c , 3^d , 3^e , are engaged with the vertical slots, 6, of the bars, 1 and 2, of this first rigid angle by thrusting said partition bars endwise horizontally into said slots, 6, the horizontal ribs, m , on the end portion of said partition bars engaging the slots, 8, of the frame bars. The corner block, N^1 , is now entered 35 by horizontal movement between the partition bars, 3^b and 3^e , the ends of the grooves n^3 on the right angle faces of said block, N^1 , engaging the ribs, m^1 , of said partition bars, 3^b and 3^e , and sliding thereon as the block, N^1 , moves into its position at the 40 corner of the frame where the horizontal ribs, m^2 , of the frame bars engage the horizontal grooves, n^2 , of the block. The partition, 4^a , is now inserted vertically, its 45 notches, 10, interlocking with the notches, 9, of the partitions, 3^b and 3^e , while its ends enter the slots, 7, of the frame bars, 1 and 50 2, the face of said partition, 4^a , toward the block, N^1 , which may be referred to as the inner face, being plain, that is, without ribs, permitting it to be entered thus in close contact with the oblique face of the 55 block, N^1 . Rectangular block, N^2 , and larger right angular blocks, N^3 , N^4 , are now slid into place between the partition plates, 3^a , 3^b , 3^c and 3^d , the lateral grooves n^2 , of the block, N^2 , and the ends of the grooves n^3 60 on the oblique faces of the blocks, N^3 , N^4 , engaging the horizontal ribs, m^1 , of the partitions, 3^a , 3^b , 3^c and 3^d , respectively, the groove, n^1 , on the inner face of the block, N^2 , engaging the rib, m^3 , on the outer face 65 of the partition, 4^a , and the grooves, n^3 , of

the oblique faces of blocks, N^3 , N^4 , engaging the ribs, m^2 , of the frame bars, 1 and 2. The partition plate, 4^b , is now entered vertically, its ends engaging the slots, 7, in the frame bars, 1 and 2, and its notches, 10, interlocking with the notches, 9, of the partition plates, 3^a , 3^b , 3^c and 3^d , said partition, 4^b , being plain on its inner face so that it may be thus entered in proper close relation to the blocks, N^2 and N^3 , N^4 . 75

Blocks, N^4 , N^4 , N^4 and N^5 and N^6 , are now slid into their places between the partitions, 3^a , 3^b , 3^c , 3^d and 3^e , their lateral grooves engaging the ribs, m^1 , of said partitions, the end of the groove, n^3 , on the oblique face of the block, N^6 , engaging a rib, m^2 , on the partition, 3^e , the groove, n^1 , on the inner faces of at least one of the blocks, N^4 , N^4 , N^4 , engaging the rib, m^3 , on the outer face of the partition, 4^b , the groove, n^3 , on one right angular face of the block, N^5 , engaging the rib, m^1 , on the frame member, 2, and the groove, n^3 , on the oblique face of the block, N^6 , engaging the rib, m^1 , on the frame bar, 2. 90

The partition, 3^b , being the last partition to be engaged at its opposite ends with the frame bars, 1 and 2, respectively, the method of assemblage from this point differs slightly from that pursued hitherto. The rectangular blocks N^7 , N^7 , N^7 , of the next row, the large triangular blocks, N^8 , N^9 , of this row, the rectangular blocks, N^{10} , N^{10} , N^{10} , and the two triangular blocks, N^{11} , N^{11} , of the next row and the small final corner triangular block, N^{12} , constituting all the remaining blocks to be assembled in the manner now being described are now slid in between the partitions of the first set. The rigid angle formed of the other frame bars, 1 and 2, is now positioned for being advanced in the direction of the partitions of the first set for entering the ends of said partitions endwise in the slots, 6, of said frame bars, 1 and 2, which constitute said second rigid angle, and simultaneously with the entering of these partitions into the frame bar slots, the ends of the frame bars forming said second rigid angle are engaged with the ends of the first rigid angle, said frame bars being reciprocally tongued and mortised for said engagement, and the engaged ends of the frame bars are securely pinned together completing the rigid cell-encompassing frame. 105

The blocks last entered comprising the three rows mentioned may now be moved to space the row, N^7 , N^7 , N^8 , N^9 , away from the row, N^4 , N^4 , N^4 , N^5 , N^6 , enough to permit the entry vertically of the partition, 4^c , 110 its ends engaging the slots, 7, of the side bars, 2, 2, of the frame and its notches, 10, interlocking with the notches, 9, of the partitions of the first set, said partition, 4^c , being perfectly plain on its inner side to 115 120 125 130

ward the row of blocks, N^4 , N^4 , N^4 and N^5 and N^6 , and the absence of the remaining partitions of the second set permitting the blocks of the remaining rows to be spaced 5 away from the blocks of the row, N^4 , N^4 , N^4 , N^6 , N^6 , sufficiently to admit the ribs, m^3 , on the outer side of said partition plate, 4^c .

The next row of blocks, N^7 , N^7 , N^7 , N^8 , 10 N^9 , is now pushed back against the partition plate, 4^c , the grooves, n^1 , on the inner faces of the blocks of this row engaging the ribs, m^3 , on the outer face of the partition, 4^c , and the groove, n^3 , on the oblique face of 15 the right angle block, N^8 , engaging the rib, m^2 , on the frame bar, 1. The row of blocks, N^{10} , N^{11} , N^{11} , will now be found spaced away from the row N^7 , N^7 , N^7 , N^8 , N^9 , sufficiently to permit the introduction vertically 20 of the partition, 4^d , whose inner face is plain and outer face is ribbed, said partition, 4^d , has ribs, m^3 , only at the middle for engaging the groove, n^1 , of the block, N^{10} , interlocking with the partitions of the other set 25 in the same manner as above described in respect to partition, 4^c . The blocks of the row, N^{10} , N^{11} , N^{11} , may now be advanced against the outer face of the partition, 4^d , the grooves, n^1 , of these blocks engaging the 30 ribs, m^3 , of the partition, 4^d .

The final corner block, N^{12} , being now forced snugly back into the rigid angle of the encompassing frame, the partition, 4^c , is introduced vertically, said partition being plain upon both faces and interlocking simultaneously with the frame bars, 1 and 2, and with the partitions, 3^d and 3^e , of the first set. This final partition plate is now secured in a familiar manner by screws, X , 40 set into the frame bars at the ends of said partition plate; and this plate being thus locked in the frame blocks all the preceding elements, since there is no partition plate without at least one rib for engagement with a block, and the insertion of the last partition plate insures against disengagement of said ribs by lateral movement of the blocks.

I claim:—

50 1. A printing plate base comprising a rigid encompassing frame and intersecting partitions subdividing into cells the space enclosed by the frame; blocks occupying the respective cells; the partitions being interlocked at their intersections and the enclosing frame bars, partitions and blocks having interlocking ribs and grooves by whose interengagement the partitions and blocks respectively lock each other against withdrawal from the frame bars.

55 2. In the construction defined in claim 1 foregoing, the partitions being oblique with respect to the encompassing frame bars and the two intersecting sets of partitions having intersections at the vertical planes of the

inner faces of the encompassing frame bars, the said frame bars having transverse slots meeting at said faces for receiving the ends of the partitions; and horizontal slots intersecting the vertical slots at the intersections 70 of the latter, one set of said partitions having longitudinal ribs which engage the horizontal slots in the frame bars when said partitions are engaged in the vertical slots; whereby said partitions of said set are prevented from being enterable or withdrawable transversely and are adapted to be entered longitudinally into the frame bars, the other set being plain-surfaced at the ends which engage the frame bar slots, whereby 75 they are enterable and withdrawable transversely.

3. In the construction defined in claim 1 foregoing, the frame bars having transverse slots for entering the ends of the partitions, 80 and longitudinal slots crossing said transverse slots; one set of partitions having longitudinal ribs extending to their ends adapted to engage the longitudinal slots of the frame bars when the partitions are entered 85 longitudinally into engagement with said frame bars, and the other set of partitions having at the end portions which engage the frame bars plane faces whereby they are enterable transversely into the transverse slots 90 of the frame bars.

4. In the construction defined in claim 1 foregoing, the cells having their walls which are formed by one set of partitions and the frame bars horizontally ribbed and one of 100 the remaining walls formed by the other set of partitions plain-surfaced; whereby the blocks are enterable horizontally along the first mentioned ribs, and the second mentioned partitions are then enterable transversely to 105 close the cells and retain the entered blocks.

5. In the construction defined in claim 1 foregoing, the cells having their walls which are formed by one set of partitions and the 110 frame bars, horizontally ribbed, and one of their walls formed by the other set of partitions plain-surfaced; whereby the blocks are enterable horizontally along the first mentioned ribs and the second mentioned 115 partitions are then enterable transversely to close the cells and retain the entered blocks, the opposite side of the plain-surfaced partitions at at least one cell being ribbed for engagement with the groove of a block of 120 the next outer row; whereby said last mentioned block lock the second mentioned transversely insertable partition against transverse withdrawal.

6. A printing plate base comprising a 125 rigid encompassing frame and intersecting partitions subdividing into cells the space enclosed by the frame; blocks occupying the respective cells; the partitions being interlocked at their intersections, the enclosing 130

frame bars, partitions and blocks having interlocking ribs and grooves by whose interengagement the partitions and blocks respectively lock each other against withdrawal from the frame bars, the finally inserted partition being plain-surfaced on both sides and means independent of the other

partitions and of the blocks for securing it at its ends in the frame bars against vertical withdrawal.

In testimony whereof, I have hereunto set my hand at Bath, N. Y., this 12th day of March, 1923.

JOHN W. PITTS.
